MACHINE FOR TEARING PAPER

John Stuart Fleming, Niagara Falls, N.Y., assignor to
Flexite Company, Inc., Niagara Falls, N.Y., a corpora-
tion of New York

Filed Apr. 24, 1962, Ser. No. 189,861

3 Claims. (Cl. 225—99)

The invention relates to machines for tearing paper, particularly for tearing a paper work sheet into parallel strips, this application being related to the Fleming Patent No. 2,913,160 entitled Machine for Tearing Paper, for providing said strips with the soft cushioned edge disclosed in the Fleming patents dated October 21, 1958, Nos. 2,856,938 and 2,856,939, and No. 2,771,084 dated November 20, 1956.

In the machine of said patent the paper tends to tear beyond the angle of divergence of the belts, resulting in an imperfect irregular soft edge, due to the belts failing to hold the work sheet down tightly to the lower of the cylinders as it is torn.

An object is to provide such a machine adapted to hold the work sheet down tightly to a lower or main cylinder and firmly control the direction of movement of the work sheet while the work sheet is being torn, so that the tearing is forced to take place at the precise angle of divergence of the endless belts, resulting in a perfect regular soft edge.

The invention consists in the novel construction and combinations of parts hereinafter set forth in the claims.

In the accompanying drawings:

FIGURE 1 is a side elevation of the machine with one side frame plate removed.

FIGURE 2 is a plan view of the machine.

FIGURE 3 is a perspective view of one side portion of the machine showing one set of the belts 3 and 5, with both frame plates being removed.

FIGURE 4 is a detail section on the line 4—4 of FIGURE 1.

FIGURE 5 is a detail fragmentary transverse section of the strips on a much enlarged scale, showing the soft cushioned edges resulting from the tearing.

Referring to the drawings, the machine for tearing a paper work sheet A into parallel strips A' comprises the following: Two parallel longitudinally approximated upper and lower cylinders 1 and 2 slightly spaced apart from each other. A vertically directed endless belt 3 passing around and over the lower of said cylinders 2, thence under and around the upper cylinder 1, thence around and over an upper end pulley 4 thereof and back to said lower cylinder, said lower cylinder 2 forming the lower end pulley of said belt. Duplicate horizontally directed endless belts 5 passing around and over said lower cylinder 2, one at each side of said belt 4 and of said upper cylinder 1 along arcuate parallel paths, the horizontally directed endless belts having their inner edges slightly spaced apart and approximated to the edges of said vertically directed belt in the plane passing through the axes of said cylinders, said belts crossing each other at 2' immediately below said plane, the passage of said vertically directed belt around and under the upper cylinder and of said horizontally directed belts around and over the lower cylinder being along arcuate diverging paths, thence around and under a guide pulley 6 thereof and thence around and under a guide pulley 7 and 8 thereof, back to said lower cylinder 2. Said one belt 3, said duplicate belts 5 and said upper cylinder 1 have similar narrow widths, much less than that of the lower cylinder 2. The diameter of the lower cylinder is much greater than that of the upper cylinder 1. The paper work sheet A is fed between said one belt 3 and said duplicate belts 5 where they pass over the lower cylinder 2 being torn

2

into strips A', certain of which pass around the upper cylinder 1, between the upper cylinder and said one belt, and others of which pass around the lower cylinder 2 between the lower cylinder and said duplicate belts 5, along arcuate diverging paths.

The passage of said one belt 3 around the lower cylinder 2 is for about 300 degrees and around the upper cylinder 1 for about 120 degrees. The passage of said duplicate belts 5 around the lower cylinder 2 is for about 120 degrees and around the guide pulley 6 for about 90 degrees.

Said belts 3 and 5 and said upper cylinder 1 are provided in duplicate at opposite sides of the machine. Said lower cylinder 2, the upper end pulley 4 of said belt 3, said guide pulley 7 and the end pulleys of said duplicate belts 5 may be wide enough to carry both sets of the duplicate belts 5.

Said upper cylinder 1, said guide pulley 6, and one end pulley 7 of said duplicate belts 5 are shown as of similar diameter and tangential to said lower cylinder 2.

Said duplicate belts 5 are capable of having their inner edges spaced apart varying distances from the edges of said one belt 3 where they are approximated in said plane to vary the breadth and softness of the soft edges of said strips resulting from said tearing. Said cylinders and said pulleys are rotatably mounted in a fixed frame 9, a drive gear 10 upon the shaft of the guide pulley 6 meshing with a pinion 11 upon the shaft of said lower cylinder 2, thereby rotating said cylinders 1 and 2 and driving said belts 3 and 5 in opposite directions.

The above described machine provides means for continuously and simultaneously gripping the work sheet A fed between the belts 3 and 5, at said plane, gripping and dragging said strips A' between said belts and said cylinders along arcuate diverging paths, and tearing the work sheet along an unweakened line of straight direction into said strips.

The soft edges of said strips A' may be serrated or otherwise patterned, due to the approximated edges of said belts being similarly patterned, this feature being not shown.

Winding rollers, not shown, may be provided upon which the strips A' may be wound.

The soft cushioned torn edges B of said strips A' resulting from said tearing are beveled at B' upon one side thereof, as shown in FIGURE 5 and may be provided with the thin superficial coating of water repellent reinforcing material upon their non-beveled sides as shown in said Fleming patents.

The belts 3 and 5 being narrow, the use of V belts engaging V grooves of the cylinders and pulleys is made possible.

Due to the aforesaid, the machine is enabled to be run faster and at the same time to turn out better products or strips A' one of about 1½ inch width which may be later divided transversely into parts and two narrow ribbon strips each of about ¼ inch width, all of said strips having the opposite edges thereof constituted by the soft cushioned soft edge B. These figures are subject to variation.

I claim:

1. A machine for tearing a paper work sheet into parallel strips, comprising: upper and lower parallel longitudinally approximated cylinders slightly spaced apart from each other, a vertically directed endless belt passing around and over the lower cylinder, and thence around and under the upper cylinder, duplicate parallel horizontally directed endless belts passing around and over the lower cylinder one at each side of said vertically directed belt and of said upper cylinder, along parallel paths, said horizontally directed belts having their inner edges slightly spaced apart and approximated to the

edges of said vertically directed belt in the plane passing through the axes of said cylinders, said belts crossing each other immediately below said plane, the passage of said vertically directed belt around and under the upper cylinder and of said horizontally directed belts around and over the lower cylinder being along arcuate diverging paths.

2. A machine for tearing a paper work sheet along an unweakened line into parallel strips, as defined in claim 1 in which the passage of said vertically directed belt around the lower cylinder is for about 300 degrees and around the upper cylinder is for about 120 degrees, and in which the passage of the horizontally directed belts around the lower cylinder is for about 120 degrees and around its guide pulley is for about 90 degrees.

3. A machine for tearing a paper work sheet along an unweakened line into parallel strips, as defined in claim 1, in which said horizontally directed belts are

capable of having their inner edges spaced apart varying distances from the edges of said vertically directed belt where they are approximated in said plane to vary the breadth and softness of the soft edge resulting from said tearing.
